UNITED STATES PATENT OFFICE

2,570,671

GUARDED KNIFE FOR CUTTING BUTTER
AND CHEESE

John F. Hartman, Allentown, Pa., assignor, by
mesne assignments, of forty per cent to John
B. Reinhard, Allentown, Pa.

Application September 20, 1948, Serial No. 50,073

3 Claims. (Cl. 30—286)

1

This invention comprises novel and useful improvements in a knife and more specifically pertains to a knife especially adapted for paring or slicing clinging substances such as butter or cheese.

The primary object of the invention is to provide a knife capable of slicing cheese, butter or other substances which tend to cling to the blade, with an improved non-clinging slicing action.

An additional object of the invention is to provide a knife in accordance with the foregoing object, which may be converted with facility and celerity from its non-clinging use into a construction supplying the functions of a conventional knife.

A further object of the invention is to provide a knife conforming with the preceding objects, which may be safely locked in either its non-clinging or its conventional knife positions.

A very important feature of the invention comprises providing a movable guard for a knife blade having a guide surface merging into the cutting edge of the blade for separating slices of material severed by the knife from the uncut material.

An additional feature of the invention resides in an improved pin and slot construction for selectively fastening the guard in its operative or inoperative positions.

And a final feature to be specifically enumerated herein comprehends the provision of an anti-friction member recessed and journalled in the guide surface of the guard for detaching the slices severed by the knife from the blade thereof.

These, together with various ancillary features and objects of the invention which will later become apparent as the following description proceeds, are attained by this device, a preferred embodiment of which has been illustrated by way of example only in the accompanying drawings, wherein:

Figure 1 is a side elevational view of the knife with its guard in operative position;

Figure 2 is a top plan view of the device as shown in the position of Figure 1;

Figure 3 is a side elevational view of the device in the position shown in Figure 1 but from the other side thereof;

Figure 4 is a side elevational view of the device of Figure 1 but with the guard in its inoperative position; and

Figures 5-7 are vertical transverse sectional detail views taken respectively upon the planes of the section lines 5—5, 6—6 and 7—7 of Figure 1.

Referring now more specifically to the accompanying drawings, wherein like numerals design-

2

nate similar parts throughout the various views; it will be seen that the numeral 10 designates a knife blade of any suitable shape and construction but which may be conveniently provided with the customary bevelled and sharpened knife edge 12 to adapt the blade for paring, slicing or the like operations.

The blade 10 upon one side thereof is provided with a guard 14 which is of substantially the same 10 dimensions and contour as the blade 10 while a handle 16 is secured to the underside of the blade 10, opposite the guard 14, but overlying only the rear or shank end of the blade 10, the handle and blade being rigidly attached to each 15 other as by rivets or other fasteners 18 and 20.

The rivet 18 as will be readily seen by reference to Figures 2 and 7, extends entirely through the handle, guard and blade, for rigidly attaching these parts together, and serves as a fulcrum pin 20 by means of which the guard 14 is pivotally secured to the blade and handle. The rivet 20, likewise is of a sufficient length to extend laterally from the blade 10, and also extend through the side of the guard 14 as indicated in Figures 25 and 6. The rivet 20 is rigidly and preferably immovably secured in both the handle 16 and the blade 10, and has an end protruding laterally from the side of the blade 10 opposite the handle 16, which protruding portion constitutes a stop pin as set forth hereinafter.

A pair of arcuate guide and locking slots 22 and 24 are formed in the marginal edge of the guard 14 and are preferably struck upon the same radius with the fulcrum pin 18 as a center, and of a radius equal to the distance from the fulcrum pin 18 and the stop pin 20, so that one of the slots 22 or 24 may be selectively engaged upon the pin 20 to constitute a stop and locking means for the guard in either its closed or open position as shown respectively in Figures 1 and 2 and in Figure 4.

The width of the guard 14 is preferably such and its shape is such that that what may be termed the lower marginal or side edge of the guard is disposed a slight distance from the bevelled knife edge 12, to provide a clearance therefor, whereby the guard will snugly overlie the entire cutting portion of the blade 10 except for its bevelled edge 12.

50 As will be readily seen by reference to Figures 1 and 5, the lower surface of the guard 14 adjacent the bevelled edge 12 when the guard is in its operative or assembled position upon the knife blade, is bevelled and provided with one or more recesses 26 in which are suitably journalled roll-

ers 28 for a purpose which will later become apparent. This bevelled surface of the guard 14 indicated by the numeral 30 in Figure 5, is so shaped as to merge into the bevelled surface 12 of the knife blade, and form a continuation thereof. The rollers 28 may be of any suitable construction and are preferably axially journaled in any desired manner in the recesses 26.

The operation of the device is as follows:

With the guard folded about its fulcrum pin 18 into its closed position or operative position upon the blade 10, as shown in Figures 1-3, it will be seen by reference to Figure 5 that the device may be employed to sever butter, cheese or other clinging substances, whereupon the slice so severed will slide up the bevelled surface 12 of the knife blade, over the smoothly contoured concave surface of the guard, and thence over the antifriction roller 28, to be thus readily detached from the piece of material being sliced. The roller 28 serves to lift the slice of material, so severed, from its intimate clinging contact with the contoured surfaces of the blade 12 and the surface 30, whereby the slice may be readily disengaged from the knife. It will be noted that in this position, the locking slot 22 has received the locking pin 20, whereby the guard is firmly positioned in position upon the knife blade.

Alternatively, the guard may be pivoted into its open position as shown in Figure 4, whereupon the pin 20 is engaged in the slot 24 to limit the opening movement of the guard, and thus completely expose the knife blade 10 and its cutting edge 12 whereby the same may be employed in the manner of a conventional knife.

From the foregoing, it will be seen that there has been provided a knife having a dual function or purpose and which is of economical and dependable construction.

Since numerous modifications will readily occur to those skilled in the art after a consideration of the foregoing description and the accompanying drawings, it is not desired to limit the invention to the exact construction shown and described, but all suitable modifications and equivalents may be resorted to, falling within the scope of the appended claims.

Having described the invention, what is claimed as new is:

1. A knife comprising an elongated flat blade member having a cutting portion and a handle receiving portion, a handle fixedly attached to

one side of said handle receiving portion and co-extensive therewith, an elongated guard movably attached to the other side of said handle receiving portion and co-extensive with said blade member, said guard having a flat inner face abutting one side of said blade member, the other side of said guard including a beveled lower edge, said cutting portion of said blade member including a beveled cutting edge, said beveled lower edge of said guard merging with said beveled cutting edge of said blade and forming a continuation thereof, said guard having an elongated recess therein communicating with said beveled lower edge thereof and extending longitudinally of said guard, and a roller journaled in said recess and extending outwardly thereof, said guard being pivotally attached to said handle receiving portion intermediate the ends of the handle receiving portion whereby said guard is movable into operative position with the beveled lower edge thereof merging with the beveled cutting edge of the blade member and into its inoperative position with the guard overlying the handle receiving portion only of the blade member, and stop means engaging the guard member when the latter is in its operative and inoperative positions.

2. The combination of claim 1 wherein said stop means includes a pair of arcuate slots in said guard member, each of said slots being concentric with the pivot point of the guard and communicating with the lower edge of the guard on opposite sides of the pivot point thereof, and a pin extending through said handle and handle receiving portion and receivable in said slots.

3. The combination of claim 2 including a common fastener securing the handle to the handle receiving portion of the blade and comprising a pivot for said guard.

JOHN F. HARTMAN.
